UNITED STATES PATENT OFFICE.

CYRUS W. BASSETT, OF MAPLEWOOD, NEW JERSEY, ASSIGNOR TO ELEVATOR SUPPLIES COMPANY, INC., A CORPORATION OF NEW JERSEY.

BARLOCK FOR ELEVATOR DOORS.

Application filed August 8, 1923. Serial No. 356,395.

The present invention relates to barlocks for elevator doors, and more particularly to a combination lock and switch, by means of which an elevator door may be locked in position, and by which the elevator operating circuit may be opened and closed with the opening and closing movements of an elevator door.

The form of barlocks or interlocks heretofore employed in connection with elevator doors for opening and closing the doors and simultaneously therewith opening and closing the elevator operating circuit, have not been satisfactory in operation, because of the fact that the electrical contact in the switch varied with slight movements of the elevator doors. The variations in the switch contacts resulted in variations or interruptions in the power transmission for operating the elevator, and consequently in inferior elevator operation. The switches heretofore employed have also been unsatisfactory because of the fact that they became more inefficient with wear, and soon wore out, because of the slight movements of the elevator door, such as would be caused by wind in the elevator shaft, or air currents due to the movements of the elevator in the shaft, which caused wear due to the inflexibility of the parts to permit such movement. None of the devices heretofore employed as far as I am aware have overcome the difficulties in power transmission or provided means whereby the transmission of current through the switch would be constant after contact has once been made.

It is the primary object of the present invention to provide a barlock and switch for elevator doors which will lock the door in position, and which in locked position will provide a suitable contact which will permit slight swinging of the door in closed position without interfering with the electrical contact in the switch.

Another object of the invention is to provide a barlock and switch in which electrical contact cannot be made until the door is locked in position by the locking means employed, and in which the head of the locking bar will be guided into position in the barlock casing, and in which the conducting member mounted upon the barlock head will be guided into contacting position between the conducting plates in the casing.

A further object of the invention is to pro-

vide means whereby the various parts of the device may be readily assembled or taken apart for cleaning or for replacement of worn parts, and which may be manufactured at a low cost.

A further object of the invention is to provide a barlock and switch in which the switch elements will maintain substantially perfect contact irrespective of wear of the parts and in any position of the conducting members relative to each other.

A further object of the invention is to provide means whereby metallic particles which may be abraded from the contact surfaces of the switch elements may not cause short circuiting between the plates when the circuit is open.

With these and other objects in view the invention comprises the various features hereinafter described and more particularly defined in the claims.

In the accompanying drawings illustrating the invention

Fig. 1 represents a vertical section through a barlock and switch, showing the locking bar head in locked position in the barlock casing, and the conducting roller in position between the conducting plates;

Fig. 2 is a section taken through section 2—2 of Fig. 1;

Fig. 3 is a section taken on the line 3—3 of Fig. 1 with the locking head removed to show a top view of the insulating block and conducting plates mounted thereon;

Fig. 4 is a perspective view of the block upon which the conducting plates are mounted;

Fig. 5 is a detailed part sectional view of the locking bar head showing the means by which the roller is mounted in the head; and

Fig. 6 is a view showing the manner of mounting the casing and bar lock in connection with an elevator door.

Referring more particularly to the drawings, 10 indicates a casing which is attached to the frame of an elevator door, as shown in Fig. 6, and to which the leads 12 of the controller circuit of an elevator are conducted through a suitable conduit. The leads 12 are attached by suitable connections 100 to two flexible plates or spring blades 14 and 16, which are suitably insulated from each other. These plates are preferably made so as to be interchangeable, and are composed preferably of three parts or laminations. 110

A conducting member 18 in the form of a metallic cylinder is loosely carried by a locking bar 20 and is adapted to be placed in position between the plates so as to conduct current or to close a circuit through the plates. The bar 20 is carried in suitable guides 22-24 on an elevator door 26, the head of the bar being supported by means of a stop 28 so as to hold the bar in position for engaging the entrance or opening to the casing 10.

The conducting member 18 is a hollow metallic cylinder and is carried by means of a pin 30 in the head of the locking bar, which is composed of insulating material. The diameter of the holding pin 30 is somewhat smaller than the diameter of the opening through the cylindrical roller 18, so as to permit movement of the roller 18, on the pin with respect to the head. The roller is cylindrical in shape so as to permit movement of the roller upon the head to attain an even wear upon the surface of the roller and thereby prevent poor contacts between the plates and the roller.

Referring more particularly to Figs. 1 and 2 of the drawing, leads from the controller circuit pass into the casing through a conduit 32 and are attached to suitable terminals upon an insulated support 34 at the top of the casing. From the terminal plates of the respective terminals and leading to the blades or conducting plates 14 and 16 are insulated lead wires 36 and 38 which are preferably soldered into the blades between the laminations thereof, and are held in place in the casing by means of supports 40 and 42 which are attached to the casing by suitable means, such as rivets or screws.

Portions of the casing around the support or holding member 34 and the supports 40 and 42 for the lead wires are suitably insulated from the metallic casing by means of suitable insulating material 46 and 48, by means of which short circuits between various parts of the device are prevented.

In order to guide the locking head of the locking bar 20 into position in the casing 10, suitably flanged portions or outwardly extending plates 50 and 52 are provided, by means of which the head is guided laterally into position. Upon the lower portion of the locking head are inclined portions or surfaces 51 and 53 which serve during closing movement of the door as a cam, operating upon an edge 56 of the casing to lift the head into position within the casing. By means of the lifting movement, the head is raised so that the roller 18 is brought over the plates 14 and 16 in position to be lowered into contact with the plates. After the lower shoulder 54 upon the head has passed the upwardly bent support 56, which serves as a guide to attain the proper elevation of the head, the locking head drops into position

upon a support 58, shown in Fig. 1, and simultaneously the conducting roller 18 is wedged in between the plates 14 and 16, causing them to spread outwardly a short distance so as to attain a tight hold upon the roller and thereby to form an admirable contact for conducting current therethrough.

The relative positions of the guide 56 with respect to the shoulder 54 and the plates 14 and 16 with respect to the roller 18 are such that the shoulder 54 will have passed the inner edge of the guiding portion 56, thus locking the head against withdrawal thereof, before the roller comes into contact with the plates. By this means the door becomes locked in position before the controller circuit of the elevator is closed, and the elevator cannot therefore be operated before the door is locked in position.

The construction of the conducting plates 14 and 16 and the means of supporting them within the casing forms one of the important features of the invention which will now be described. An insulating block 2, which is preferably composed of three sections, is provided for rigidly holding the plates in parallel position. The plates are preferably screwed into place on the outer sections of the block by means of screws as shown more particularly in Fig. 2 of the drawings. The base of the block is slightly curved upwardly at the sides so as to permit a side rocking movement of the block and plates, as is shown more particularly in Fig. 4 of the drawings. In order that the block may be withdrawn from the casing for cleaning or other purposes, the block is provided with suitable grooves 4 and 6, which are adapted to cooperate with an upwardly bent plate 8, the sides of which fit into the grooves. The plate 8 is preferably attached to the base of the casing by means of rivets, which are adapted to register with corresponding depressions 3 and 5 in the under side of the block which are slightly larger than the heads of the rivets so as to hold the block and still permit a limited movement of the block in place in the casing. When it is desired to withdraw the block and plates from the casing, one of the covers 9 or 11 is removed and the block is slightly raised and moved sideways so as to permit sliding over the rivets, and along the edges of the plate 8. The side portions of the block 2 are curved or pointed towards the front and back ends of the block, so as to permit rotary or swinging movement of the block in a horizontal plane. By the means above described the block is loosely held in position within the casing and may be moved either in a horizontal plane or in a vertical plane at right angles to the plates. In the central section or mid-section of the block 2 are parallel grooves 60, 62 and 64, as shown more particularly in Fig. 4 and

Fig. 2, which are adapted to catch any particles which may fall from the contracting members due to abrasion from the roller or the surface of the plates, and which might 5 otherwise cause a short circuit between the plates. The grooves serve as air gaps to further insulate the plates from each other, and by this means all danger of obtaining a short circuit between the plates is avoided. 10 The edges of the plates 14 and 16 are bent outwardly at the top and also at the end portions in order to provide means for guiding the roller 18 into position between the plates. The roller 18 is adapted for movement 15 in a plane at right angles to the pin 30 and also for limited movement in every direction without interfering with the contact between the plates. It will be noted that by this construction a rigid and complete contact 20 between the roller 18 and the plates 14 and 16 is provided, which will permit movement of the plates and roller together without interfering with the contact between them. 25 It is to be understood that various changes or modifications may be made in the various parts of the device within the scope of the claims, without departing from the spirit or scope of the invention.

30 Having thus described the invention, what is claimed as new is:

1. In an electric switch, a pair of resilient conducting plates constituting circuit terminals, a bridging member adapted to be sprung into circuit closing position between said terminals, a bar connected to said bridging member to move said member into and out of circuit closing position, means for loosely connecting said bar to said member to permit relative movement of said bar with respect to said bridging member in up and down and lateral directions whereby limited movement of said bar with respect to said terminals is permitted without interference with the circuit through said terminals and conducting member.

2. In an electric switch, a pair of yieldable conducting circuit terminals, a self centering conducting member adapted to be seated between said terminals to close the circuit therethrough, means for moving said conducting member into and out of position between said terminals, means for permitting relative movement between said member and said means whereby said means may oscillate in multiple directions without interfering with the contact between said member and said circuit terminals.

3. In an electric switch adapted for opening and closing an elevator controller circuit, a pair of circuit terminals, a self centering conducting roller adapted to be resiliently placed between said terminals, a bar for moving said roller into and out of engagement with said terminals, and means for per-

mitting relative movement of said bar in all directions in a plane at right angles to the axis of said roller, whereby a suitable contact between said terminals and said roller may be maintained irrespective of slight 70 movements of the bar with respect to said roller and terminals.

4. In an electric switch, a casing, a pair of yieldable conducting circuit terminals in said casing, a self centering conducting 75 roller adapted to be seated and held in pressure contact between said yieldable terminals, a bar for moving said roller into and out of engagement with said terminals, means for mounting the said roller on said 80 bar so as to provide a limited movement thereof in all directions relative to said bar whereby, when said roller is seated between said terminals, the bar may have a limited movement without interfering with the electrical 85 contact between the said roller and said terminals, and means for guiding the said bar into said casing to bring the said roller into the desired longitudinal position before said roller is seated between said terminals. 90

5. In a device of the kind described, a casing, a pair of conducting members in said casing, means for connecting said members with an electric circuit, means for holding 95 said members in a relatively fixed position with respect to each other but slightly movable with respect to said casing, a contact member, a carrying member, and means for loosely mounting said contact member on 100 said carrying member so as to permit relative movement thereof with respect to said carrying member, the said contact member being adapted to be wedged between said conducting members so as to be firmly held 105 thereby to attain suitable electrical contact, whereby said carrying means and said conducting members may have a limited movement with respect to said casing without interfering with the electrical contact between 110 said contact member and said conducting members.

6. In an electric switch adapted for opening and closing an elevator controller circuit, a casing adapted to be mounted in fixed 115 position, an insulated base in said casing, a pair of substantially parallel conducting plates having outwardly flaring edges, means for connecting said plates to said base so as to be insulated from each other, a bar having an insulated head, a conducting roller, means for mounting said roller in said head so as to permit a limited free movement therein in all directions, and means for guiding said head into said casing to bring said 120 roller into the desired longitudinal position in said casing before the said roller is brought into contact with said conducting plates.

7. In an electric switch adapted for open- 125

ing and closing an elevator controller circuit, a casing adapted to be mounted in fixed position, an insulated base in said casing, means for removably fastening the said base, 5 the said means being adapted to permit a limited turning movement of said base within said casing, a pair of substantially parallel conducting plates having outwardly flaring edges, means for mounting said plates in said casing on said base so as to be normally insulated from each other, a bar mounted upon an elevator door so as to be movable therewith, an insulated head on said bar, a conducting roller in said head 10 adapted to co-operate with said plates to close a circuit in closed position of said door, and means to permit a limited movement of said head in all directions in a plane at right angles to the axis of said roller without causing relative movement of the roller with respect to said plates.

8. In an electric switch adapted for opening and closing an elevator controller circuit, a casing adapted to be mounted in fixed position, 25 an insulated base in said casing, a pair of substantially parallel conducting plates having outwardly flaring edges, means for mounting said plates in said casing upon said base so as to be normally insulated from each other, a bar mounted upon an elevator door so as to be movable therewith, an insulated head on said bar, a conducting roller having a diameter greater than the width of said head, means for loosely mounting 30 said roller in said head so as to permit a limited free movement thereof in all directions with respect to said head, means for wedging said roller between said plates to close said elevator circuit, and flaring edges 35 on the said casing for guiding the said head into position therein before said roller is brought into contact with said plates.

9. A combination barlock and electric switch for elevator doors comprising a casing, 45 electrical contact members in said casing, insulating means between said members, circuit terminals connected to the said members, a locking bar, an insulated head carried by the said bar, a conducting roller 50 carried by the said head, a sloping support within the said casing adapted to hold said head in place longitudinally of said casing, and means for preventing withdrawal of said head from said casing without first 55 lifting the said roller out of contact with said plates.

10. A combination barlock and electric switch for elevator doors comprising a casing, 60 spring contact plates in said casing, means for holding said plates rigidly with respect to each other and slightly movable with respect to said casing, terminals connected to said plates, a conducting roller adapted to seat and make contact between 65 said plates, and means for loosely carrying

said roller to permit movement of said carrying means without causing movement of said roller.

11. A combination barlock and electric switch for elevator doors comprising a casing, 70 flexible contact plates within the casing, insulating means for holding said plates rigidly with respect to each other, said means being adapted to rock in a vertical or horizontal plane, terminals connected to 75 said plates, a conducting roller, and means for loosely holding said roller and for moving said roller into and out of contact with said plates.

12. A combination barlock and electric 80 switch for elevator doors, comprising a casing, flexible contact plates within the casing, insulating means for rigidly holding said plates, means for flexibly fastening said holding means in said casing to permit 85 movement of said plates, terminals connected to said plates, a conducting member adapted to seat and make contact between said plates, a locking bar adapted to loosely carry said conducting means to thereby 90 permit movement of said bar relative to said conducting means without breaking said contact, and means for locking said bar in position in said casing, said locking means being in such position as to cause locking 95 of said bar before contact is made between said conducting member and said plates.

13. A combination barlock and electric switch for elevator doors, comprising a casing adapted to be fastened in a door frame, 100 flexible contact plates in the casing, an insulated base for said plates adapted for a limited rocking movement, and a conductor adapted to be carried by a door, the said conductor being flexibly mounted thereon to 105 open and close a circuit between the said plates with opening and closing movements of said door.

14. A combination barlock and electric switch comprising a casing, a removable insulating base within said casing adapted for said rocking movement and limited movement in a horizontal plane, a pair of 110 spring contact plates attached to said base, and a conductor adapted to be moved into and out of engagement with said plates and adapted while in engagement with said plates to move therewith.

15. A combination barlock and electric switch comprising a casing, an insulating 115 base within said casing adapted for limited movement with respect to said casing, contact plates mounted on said base, grooves in said base to provide insulating air gaps between said plates, and a metallic conductor adapted when in position between said plates to conduct current therethrough.

16. A combination barlock and electric switch comprising a casing, a removable insulating base within said casing, contact 120

- plates mounted on said base, a conducting member adapted for positioning between said plates and to retain its position with movements of said plates, means for permitting limited movements of said base in a horizontal and a vertical plane.
17. A combination barlock and electric switch comprising a casing, an insulating block within said casing, parallel spring 10 conducting plates mounted on said block, said plates extending upwardly from said block, grooves in the block for receiving metallic particles falling from said plates to maintain insulation between said plates,
- 15 and a rod having a contact portion movably mounted thereon and adapted for positioning in said casing between said plates.
18. A combination barlock and electric switch comprising a casing, an insulating 20 block within said casing, parallel spring conducting plates mounted on said block, said plates extending upwardly from said block, grooves in the block for receiving metallic particles falling from said plates to maintain insulation between said plates, a 25 rod having a contact portion yieldably mounted thereon and adapted for positioning in said casing to attain positive contact between said plates and said contact portion, and means for holding said bar against withdrawing movement from the casing while said parts are in contact.
19. A combination barlock and electric switch comprising a casing, an insulating 30 block within said casing, parallel spring conducting plates mounted on said block and having edges flaring outwardly from said plates, grooves in said block between said plates and parallel thereto, a conducting cylinder adapted for positioning be- 35 tween said plates and for being guided into position by said flaring edges, said cylinder being slightly greater in diameter than the distance between said plates to be rigidly held between them, a bar slidably mounted 40 upon an elevator door, a locking head upon said bar adapted to carry said cylinder, means for guiding said head into said casing, and means upon said head for lifting said head when the elevator door is closed 45 so as to position said roller in the casing above said plates and thereby to be guided into position by said flaring edges, and means for locking said head in position in said casing before contact is made between 50 said plates and said conducting cylinder.
20. In a device of the kind described, a movable block, flexible conducting members attached to said block, conducting wires attached to said members, a conducting member adapted to be wedged in between said flexible conducting members, and an insulating head for carrying said conducting member adapted for positioning between said 55 conducting members.
21. In a device of the kind described, an insulating block, flexible conducting plates rigidly mounted on said block so as to be parallel with respect to each other, grooves in said block providing air gaps therein 60 between said plates, the base of said block having sides curving upwardly in a plane at right angles to said plates to permit side 65 rocking movement of said base and plates, and means in said plates for attaching conducting wires thereto.

Signed at Hoboken, N. J., this 1st day of August, 1923.

CYRUS W. BASSETT.
